UNITED STATES PATENT OFFICE.

LOUIS LEVIEN, OF NEW YORK, N. Y.

VANITY TRAY.

Application filed August 18, 1927. Serial No. 213,965.

My invention relates to a new and improved form of vanity tray.

One of the objects of my invention is to provide a sanitary and ornamental vanity tray which shall be adapted and useful for containing a number of different cosmetics and which shall also be adapted to contain other articles of personal use, such as cigarettes, jewelry and the like.

Another object of my invention is to provide a vanity tray of the above mentioned type which will be of simple and compact construction, and which shall be economical to manufacture.

Other objects of my invention will be set forth in the following description and drawing which illustrate a preferred embodiment thereof, it being understood that the above general statement of the objects of my invention is intended merely to generally explain the same and not to limit it in any manner.

Fig. 1 is a vertical central sectional view showing the improved device.

Fig. 2 is a top view on the line 2—2 of Fig. 1.

The body of the vanity tray 10 is preferably made of glass or ceramic material, although it may be made of any suitable metal or other material. Said body has an integral annular flange forming a central circular compartment 12 and an outer or lateral annular compartment 11.

The compartments 12 and 11 are closed by an intermediate cover member 13 which is provided at the top thereof with a series of depressions 15, 16, 17, 18, 19 and 20.

Said intermediate cover member 13 is also provided with a central depression having an upstanding ridge 14, which provides a finger-hold by means of which said intermediate cover member 13 can be conveniently manipulated.

The device is also provided with a top cover member 21 having a hollow head 22 into which perfume or the like may be poured. The hollow head 22 is provided with a glass stopper having a rod 23, this form of stopper being well known to the trade.

As clearly shown in Fig. 2, cigarettes may be located in the depression 20, lipsticks, for example, may be located in the depressions 16 and 17, matches may be located in the depression 19, and cakes of cosmetics and puffs may be located in the depressions 15 and 18.

The large bottom chamber 12 may contain loose powder and a large puff, for example, and small articles, such as jewelry and the like, may be located in the annular chamber 11.

It is clear that when the top cover 21 is in position that all parts of the device are enclosed and protected against dust.

It is also clear that by merely lifting the top cover 21 that all the articles located in the intermediate cover member 13 are conveniently accessible and that the contents of the chambers 11 and 12 are also conveniently accessible by lifting the intermediate cover member 13.

I have shown a preferred embodiment of my invention but it is clear that numerous changes and omissions could be made without departing from its spirit.

I claim:—

1. A vanity case having a body portion whose bottom is provided with an upstanding circular flange, an intermediate cover member located within said body portion and adapted to rest upon said flange, said intermediate cover member having a depression therein, and a top cover member located within said body portion and adapted to rest upon said intermediate cover member, said intermediate cover member having a central depression provided with an upstanding ridge to serve as a hand-hold.

2. A vanity case having a body portion having the interior thereof provided with a circular flange, an intermediate cover member located within said body portion and adapted to rest upon said flange, said intermediate cover member having a number of depressions therein and a top cover member located within said body portion and adapted to rest upon said intermediate cover member, said intermediate cover member having a central depression provided with an upstanding ridge to serve as a hand-hold.

3. A vanity case having a body portion having the interior thereof provided with a circular flange therein, an intermediate cover member located within said body portion and adapted to rest upon said flange, said intermediate cover member having a central depression provided with a ridge to serve as a hand-hold and a cover positioned upon said intermediate portion and within said body portion.

In testimony whereof I affix my signature.
LOUIS LEVIEN.
